UNITED STATES PATENT OFFICE.

JOHN H. BYER, OF ORRTANNA, PENNSYLVANIA.

SHEARS.

1,374,819.

Specification of Letters Patent. Patented Apr. 12, 1921.

Application filed July 16, 1920. Serial No. 396,651.

To all whom it may concern:

Be it known that I, JOHN H. BYER, a citizen of the United States, residing at Orrtanna, in the county of Adams and State of Pennsylvania, have invented new and useful 5 Improvements in Shears, of which the following is a specification.

This invention relates to improvements in shears and the principal object of the invention is to provide a third blade for the shears 10 with means whereby it can be used or not as desired.

Another object of the invention is to provide means for locking the main blades of 15 the shears together when the third blade is to be used, said locking member also acting to hold the third blade in inactive position when the main blades are being used.

This invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the several views, and in which:—

Figure 1 is an elevation of the shears in closed position.

Fig. 2 is a similar view with the shears in open position.

Fig. 3 is a section on line 3—3 of Fig. 1.

Fig. 4 is an edge view.

Fig. 5 is an enlarged end view showing the locking means.

Fig. 6 is a view of the central member.

In these views 1 and 2 indicate the main blades and 3 the auxiliary or third blade, which in the drawing is shown as a button hole cutter, but it will of course be understood that this blade may be made in any desired form as can also the other blades. The

handles 4 and 5 of the blades 1 and 3 are made in the usual manner while the shank 6 of blade 2 is formed from a straight piece of small dimensions and arranged to lie between the handles 4 and 5 of the other blades. The three members are pivotally connected together by the usual bolts 7 and the member carrying the shank 6 lies between the other two members. The handle 55 4 of member 1 is made thicker than the blade

part and this thick part terminates in an inclined shoulder 8 adjacent the pivotal point. The shank 6 is also of greater thickness than the blade and intermediate the said shank 6 and the blade is a wide part 9 which 60 terminates in the inclined shoulder 10 for co-acting with the shoulder 8 and on the other face this wide part tapers off and forms an off-set portion 11 which engages a recess 12 formed in the third member between its handle part and its pivotal point, the end of the off-set portion being curved as at 13 to engage a curved shoulder 14 forming the end of the recess. Thus when the shears are closed the handle portions will 70 form a snug fit with the handle portions lying in the same plane as the blade portions and the shank part 6 of the third member will make a neat fit with both of the handle members 4 and 5 of the blades 1 and 3. 75

This shank 6 may be locked to either one of the handles 4 and 5 by means of a spring pressed latch member 15 at the end of said shank engaging the pins 16 on said handles 4 and 5. Thus the third blade 3 may be 80 locked to the blade 2 so that the two main blades may be used as in the ordinary manner or the shank 6 may be locked to the handle 4 so that the blade 3 may be used. This blade co-operates with the cutting edge 17 85 formed on the rear outer face of the blade 2. The shank 6 is made slightly shorter than the handles 4 and 5 so that the latch member will occupy the space between the ends of said handles so as to not interfere with the 90 proper use of the shears.

It is thought from the foregoing description that the advantages and novel features of my invention will be readily apparent.

I desire it to be understood that I may 95 make changes in the construction and in the combination and arrangement of the several parts, provided that such changes fall within the scope of the appended claims.

What I claim is:—

1. A device of the class described comprising a pair of main blades and a third blade co-operating with the rear edge of one of the other blades, said third blade engaging the outer face of one of the main blades 105 and this main blade having a straight shank fitting between the handles of the other blades, a spring latch on the end of said shank and pins on the handles for engaging said latch. 110

2. A device of the class described comprising three superimposed blades, the central blade having a straight shank fitting between the handles of the outer blades, means for detachably connecting the shank with either of the handles of the outer blades, an offset part connecting the shank with the

blade, said offset part being beveled and provided with shoulders and the outer blades being provided with shoulders and recesses 10 for co-operating with the shoulders and recesses of the middle blade.

In testimony whereof I affix my signature.

JOHN H. BYER.
